CEMETERY VASE

Axel S. Carlson, Brooklyn, N. Y.

Application April 8, 1954, Serial No. 29,907

Term of patent 14 years

(Cl. D35—3)

Fig. 1 is a perspective view of a cemetery vase, showing my new design, with a portion of the bottom container broken away to indefinite depth.

Fig. 2 is a perspective view of my vase in another position having a portion of the bottom omitted for convenience of illustration.

The dominant features of my design reside in the portions shown in full lines.

I claim:

The ornamental design for a cemetery vase, as shown and described.
